UNITED STATES PATENT OFFICE.

GLENN H. CURTISS, OF BUFFALO, NEW YORK.

EXHAUST-HEATER FOR AIR-INLETS.

1,210,373.

Specification of Letters Patent. Patented Dec. 26, 1916.

Application filed September 18, 1915. Serial No. 51,477.

To all whom it may concern:

Be it known that I, GLENN H. CURTISS, a citizen of the United States, residing at Buffalo, in the county of Erie and State of New York, have invented certain new and useful Improvements in Exhaust-Heaters for Air-Inlets, of which the following is a specification.

This invention has particularly to do with an apparatus for heating air for the fuel mixture of internal combustion engines as used on aeroplanes and other craft operating at extremely high speeds. While having this particular relation, it is, however, capable of other uses as will be readily seen upon a full understanding thereof. The bodies of such craft are customarily given a streamline form to reduce resistance to forward movement to the minimum, and the heads only of the motor cylinders, or the exhaust pipes themselves, project beyond this streamline housing. Ordinarily the exhaust pipes are mere stubs of sufficient length to convey the exhaust gases clear of the side of the craft and the head of the operator.

It is contemplated by the present invention, accordingly, to produce an apparatus making effective use of the heating capacity of the motor exhausts, such apparatus including a casing adapted to contain a longitudinal row of the exhaust conduits in battery so that the sum of their heating capacities may be employed for a single air inlet controllable in conjunction with the fuel mixing apparatus of the motor.

It is a further object of the invention to construct the heat casing of streamline formation such that the resistance to forward movement normally occasioned by the multiple exhaust conduits on each side of the motor housing, will be cut down to the minimum.

The above and additional objects, to be hereinafter more specifically treated, are accomplished by such means as are illustrated in the drawings, described in the following specification and then more clearly pointed out in the claims, which are appended hereto and form a part of this application.

With reference to the drawings, in which there is illustrated one embodiment of the invention, and throughout several views of which like characters of reference designate similar parts, Figure 1 is a side eleva-

tion of an aeroplane as equipped with the exhaust heater of this invention; Fig. 2 is a bottom view of the heater casing *per se*; Fig. 3 is a front end view of the same, showing parts of the motor and aeroplane elements; and Fig. 4 is a partial, longitudinal, sectional view taken through the casing.

An internal combustion motor which is designated in its entirety by the numeral 10 includes a number of cylinders 11, and is so housed in the body 12 of the aircraft that the heads of the cylinders and the exhaust conduits 13 thereof are adapted to project therefrom. The exhaust conduits 13 project laterally from the cylinders 11 and lie approximately in the same longitudinal plane, one of these conduits being employed for each cylinder. Normally, projections of these conduits are made in order to convey the waste gases clear of the body 12 of the machine. It is the object of this invention, however, to inclose these continuations of the exhaust pipes by a streamline casing, which shall not only utilize the quantities of heat radiated from the pipes for the purpose of raising the temperature of the air adapted to be mixed with the hydrocarbon fuel for the motor, but which shall also cut down the resistance to forward movement otherwise offered by a battery of pipes so elongated.

The heater casing is designated by the numeral 14, being longitudinal of the streamline section clearly illustrated in Fig. 2, and having its sides 15 closed around the prolongations 16 of the exhaust conduits. Each of these prolongations includes a tube or conduit having a passage equal to and adapted to register with the passage of the exhaust pipe proper, with which it is connected through the medium of fastening means 17 operative through a joint generally designated by the numeral 18 in order to fasten the pipes 16 firmly on the extremities of the exhaust conduits, and within the heater casing at the same time.

The pipes 16 form what may be termed a heating grid or radiator, the passage of air over which will cause the temperature of the latter to be raised considerably. Air is admitted into the casing through an induction opening 19 and after circulation around the exhaust pipes 16 is drawn from the casing at the opposite end through the

conduit 20 which leads to the carbureter 21 of the motor. Preferably the conduit 20 enters the body 12 of the aeroplane along a path which takes it into close proximity 5 to the heads of the cylinders 11.

The operation of the apparatus is most efficient.

The heater warms up immediately when the motor is started and heats the air quickly 10 to comparatively high temperatures owing to the rapid radiation of heat from the waste gases through the exhaust pipe continuations 16. The air is passed successively over the conduits from front to rear, such action 15 heating it progressively to the higher temperatures desired. Besides accommodating the exhaust conduits in battery or in multiple for this heating purpose, the elongated form of the casing lends itself extremely well to 20 a streamline section, thus materially reducing the head resistance of the craft.

While in the foregoing, however, there has thus been illustrated in the drawings and described in the specification such combination and arrangement of elements as 25 constitute one preferred embodiment of this invention, it is desired to emphasize the fact that such departures from the particular embodiment disclosed may be made in 30 later adaptations of this invention as shall be recognized as within the scope of the appended claims.

What is claimed is:

1. In combination, a multiple cylinder 35 motor, exhaust conduits therefrom occupying positions substantially in the same longitudinally extending plane, and a heater casing having a longitudinal section of streamline form inclosing said conduits in battery.

2. In combination an air craft, a driving 40 motor therefor having an exhaust conduit, a stream-line heater casing disposed in a longitudinally extending plane incasing said exhaust conduit, a carbureting device for said motor, and a conduit connecting one end of said casing with said carbureter, said casing having an induction opening at its opposite end.

3. In combination an air craft having an 45 inclosed body, a motor located in said body and having an exhaust conduit projecting beyond the same, a streamline heater casing disposed in a longitudinally extending 55 plane and incasing said exhaust conduit, a carbureting device for the motor located

within the body of said air craft, and an intake air conduit interconnecting said carbureter and one end of said heater casing, said heater casing having an induction port 60 at its opposite end.

4. In combination an air craft, a multiple cylinder motor therefor, exhaust conduits for said motor lying approximately in a longitudinally extending plane, a 65 streamline heater casing, the body of which is pierced transversely by said exhaust conduits; a carbureting device for said motor, an air intake conduit connecting said carbureter with one end of said heater casing, 70 said heater casing having an induction opening at its opposite end.

5. In an air craft having a streamline body in combination, an internal combustion motor located in the body of said air 75 craft and having a multiple number of cylinders, exhaust conduits projecting without said body casing and lying approximately in the same longitudinally extending plane, an air heater casing having a streamline form, 80 transversely pierced through by said exhaust conduits in battery, a carbureting device within the body of said air craft, and an air intake connecti. the said carbureter with one end of said heater casing, said casing 85 having an air induction port at its opposite end.

6. In combination, a multiple cylinder motor, separate exhaust conduits extending therefrom, continuations for each conduit, 90 and a heater casing adapted to inclose separately the central portion of each of said continuations.

7. In combination, a multiple cylinder motor, exhaust conduits extending from the 95 motor, continuations for each conduit, a casing adapted to inclose said continuations to form a heating grid, and means connecting said continuations to said conduits and said casings concurrently.

8. In combination, a multicylinder motor, exhaust conduits extending from the motor, individual continuations for each conduit, a casing extending across said continuations intermediate their ends and adapted to separately inclose said continuations to form a heating grid, and means connecting said continuations to said conduits and said casings concurrently.

In testimony whereof I affix my signature.

GLENN H. CURTISS.
